UNITED STATES PATENT OFFICE.

LOUIS E. F. WACHTER, OF NEW YORK, N. Y.

WATCH CRYSTAL AND BEZEL.

1,308,690.

Specification of Letters Patent.

Patented July 1, 1919.

Original application filed October 17, 1917, Serial No 197,006. Divided and this application filed March 11, 1918. Serial No. 221,585.

To all whom it may concern:

Be it known that I, LOUIS E. F. WACHTER, a citizen of the United States, residing in the city, county, and State of New York, 5 have invented certain new and useful Improvements in Watch Crystals and Bezels, of which the following is a specification, reference being had to the accompanying drawing illustrative of one particular embodiment of my invention, this application being a division of my application Serial No. 197,006, filed October 17, 1917.

This invention relates to crystals as the term broadly applies, that are transparent 15 protecting covers such as are used on watches, clocks or other articles where the dial must be visible and at the same time require protection, and relates in particular to the combination of such crystal and its 20 supporting means usually referred to as the bezel. Instead of the use of glass for crystals, celluloid and other transparent materials are used, and in the case of celluloid the physical characteristics of the material necessitate the methods of attachment.

Among the objects of this invention are to provide better means of overcoming the difficulties in attaching celluloid or like material, and to secure such by means assuring under all conditions a satisfactory joint 30 between the transparent disk and the attaching rim under the varying conditions to which the material is subjected. I accomplish this by making a pliable, resilient and transparent face cover, the form and construction of which are such that any shrinkage which might take place will not produce a loosening in the joint or permit the crystal 35 to fall out.

40 The demand for non-breakable watch crystals necessitates the production of an article which will overcome all the disadvantages which crystals heretofore might possess, in particular the loosening of the same from 45 their fastenings due to shrinkage, owing to the character of the composition of such non-breakable crystals.

The particular species of construction to which this divisional application is addressed, is shown in one form in the accompanying drawing, in which:

Figure 1 is a fragmentary central horizontal section of the crystal showing the same in position in the bezel with however the bezel separated from the watch case;

Fig. 2 is a similar view showing however the bezel pressed down into position and the edge of the crystal pressed outwardly.

The crystal F is shown in a fragmentary illustration with its edge in position with 60 relation to the bezel F', which bezel has the inwardly-projecting edge and the usual foot for attachment to the watch center. Associated therewith is the dial G. From this it will be seen that the bend f' in the flange 65 of the crystal rests on the surface of the dial and the upper side of the flange engages the under side of the bezel, while the upper inwardly-projecting edge of the bezel engages the side of the crown of the crystal. 70

These crystals may be fitted tight in the bezel opening, which will be done by inserting from the inside toward the outside of the bezel, or the crystal may be placed in position and the bezel snapped over the 75 flange, the upwardly curved edge of the crystal being pressed by the under portion of the bezel F', so that the flange of the crystal forms a resilient elastic joint in engagement with the surface of the dial.

Variations in the thickness and dimensions of material become important in the new art of the use of celluloid for this purpose, and details as to these are important, but various modifications from the particular form shown, may be made in construction without departing from my invention.

By the practice of my invention relatively thin material may be used for the face of transparent closure, whereby the desired 90 elasticity and spring for insertion, can be provided, and proper transparency in such materials, as celluloid, is assured, while the other advantageous features necessary for commercial success are accommodated. In 95 this species of my invention the elasticity and spring of the peripheral portions co-operate in making my invention most effective.

What I claim and desire to secure by Letters Patent is:

1. In a watch or like article, a bezel, a crystal having a cupped-face portion, a side wall engaging the inner periphery of the bezel and extending in a flange edge more 105 flexible than the face portion engaging the under side of the bezel and the surface of the dial or adjacent watch parts.

2. In combination in a watch or like article, a bezel, a crystal having a cupped- 110

face portion merging into a thin flexible brim-portion constituting the retaining edge, and engaging the under side of the bezel and the surface of the dial or adjacent watch parts.

- 5 3. In combination in a watch or like article, a dial, a bezel and a crystal, said crystal having a peripheral off-set from its surface terminating in a flexible flange-brim, 10 and held between the under side of the bezel and the dial.
- 10 4. In combination in a watch or like article, a bezel, a crystal having a face-portion

tion the peripheral edge thereof engaging the inner periphery of the bezel and having 15 a curved flange edge portion more flexible than the face portion forming a brim and engaging the under side of the bezel and the surface of the dial or adjacent watch parts.

20 Signed at New York, this 9th day of March 1918.

LOUIS E. F. WACHTER.
